(57) **CLAIM**

I claim the ornamental design for a garment hanger for a suit, as shown and described.

DESCRIPTION

FIG. 1 is a front view of a garment hanger for a suit showing my new design;

FIG. 2 is a right side view thereof;

FIG. 3 is a left side view thereof;

FIG. 4 is a top view thereof;

FIG. 5 is a bottom view thereof;

FIG. 6 is a rear view thereof; and,

FIG. 7 is a perspective view thereof.

The broken lines shown represent unclaimed subject matter and form no part of the claimed design.
